UNITED STATES PATENT OFFICE

MICHEL TCHOURBITCH, OF SUCY-EN-BRIE, FRANCE

AUTOMATIC TELEPHONE SYSTEM

Application filed April 4, 1928, Serial No. 267,396, and in France April 11, 1927.

The present invention relates to an automatic selector relay apparatus intended for telephony. The essential features of the new apparatus will appear from the following description:

It is known that a telephone line, to give good results, should be balanced in order better to avoid disturbances and losses due to an unbalanced state of the lines.

10 Hence, the adoption of a solution which consists in making independent the feed of each of the two subscribers (calling and called parties), while providing a free path for the modulated talking current between 15 the two subscribers. This implies the use of an incoming trunk and an outgoing trunk, connected together by means of suitable filters traversed by the modulated talking current, but opposing the passage of the feed 20 current proper.

In conformity with this principle there have been constructed a number of automatic relay telephone systems in which use is made of trunk lines, one the incoming, and the 25 other the outgoing trunk.

Each subscriber's line is crossed by two lines (incoming and outgoing) of each auxiliary line, and each point of intersection comprises two selector relays, the functions 30 of which are: first, to connect the subscriber's line with the outgoing trunk, and second, to connect the same subscriber's line with the incoming trunk of the same auxiliary line (accordingly as the subscriber is the calling 35 or the called party). The number of selector relays is then double the product of the number of subscribers by the number of auxiliary lines, which renders automatic relay telephony practically impossible.

40 Certain combinations of grouping the subscribers' lines have also been tried, these combinations consisting in considerably augmenting the number of contacts of certain relays, several subscribers being grouped on 45 the same relay and the different groupings having access only to a fraction of the total number of auxiliary lines. This results in serious difficulties in the upkeep of relays too greatly encumbered with contacts and disturbance of traffic, the number of simultane-

ous conversations in a predetermined group not being capable of exceeding a fraction of the number of auxiliary lines belonging to this group.

The automatic relay selector apparatus 55 forming the subject of the present invention, and which may be applied to all distribution networks, whatever their importance, differentiates in this regard from all automatic relay selector apparatus known at the present time, in that use is made, in combination with a line mutation relay for each subscriber, of as many selective relays (belonging to the same subscriber) as there are auxiliary lines, each line reversing relay comprising a pair of rest contacts connected to an incoming link and a pair of work contacts connected to an outgoing link, each intersection of the links of a subscriber's station with one of the trunk lines comprising a single 60 selector relay effecting simultaneously, when it is operative and by means of its two pairs of contacts, on the one hand, connection of the incoming link with the incoming trunk and, on the other hand, connection of the 65 outgoing link with the outgoing trunk, one of the two links being automatically insulated from the corresponding subscriber's line by the reversing relay of said subscriber's line, accordingly as the latter is the calling 70 or the called party.

75 By means of this combination, one and the same selector relay is capable of connecting any subscriber's line with the outgoing trunk, or with the incoming trunk, without disturbing the balanced condition of the above named circuits and the number of selector relays is only equal to the product of the number of subscribers by the number of auxiliary lines, that is to say, that in the new system, the number of selector relays is only half 80 the number of the same relays required by known systems to attain the same result.

85 Another characteristic of the invention consists in the formation of the "dial group", which comprises as many counting chains as there are digits to form a subscriber's number, each of said chains being actuated according to the counting of the units, the tens, the hundreds, and so on.

In order to avoid defective operation of the counting chains known at present (said defective operation being due to the cascade connection of the chain relays), in the present apparatus each of the numbering chains is excited by means of two distinct circuits traversed respectively by uneven (odd) current impulses flowing through the rest contact of each of the even relays, and by even current impulses shunted on each of the odd relays, the division of the impulses (produced by the counting dial of the calling party) into even and odd impulses being effected by means of a regulator called an "impulse distributor" preceding each counting group, said impulse distributor being connected with relays to automatically direct the series of impulses from one counting chain into the following counting chain, in proportion as the impulses of the same series are terminated.

Through the resolution of the impulses of the counting dial into odd and even impulses, a slight retardation in the operation of one of the counting relays can never be transmitted as a wrong number.

On the other hand, the fact that each of the counting chains is itself arranged to be controlled by two distinct circuits, the different relays of these chains operate (function) freely and independently, which eliminates adjustment of the relays, the sensitiveness of which plays only a secondary part; this is an appreciable advantage as compared with what takes place in known systems where the impulses succeed each other by means of a single circuit (cascade mounting).

All the counting groups of the new automatic relay selector circuit (groups which are, for example, two for each hundred subscribers) are connected to a single connecting group or connecting chain, formed by ten decimal relays controlled individually by a work contact of each relay of the hundreds counting chain, each connecting relay in turn controlling ten contacts, each fixed part of which terminates at the control circuit of a called subscriber's line, the movable part of each of said contacts terminating in a work contact of each relay of the units counting chain.

The complete system is represented in two views in which Figure 1 represents a number of individual equipments or subscribers' lines which cross a network of auxiliary lines of which one has been represented with its conversation cord.

Figure 2 represents a numbering group proceeding from the impulse distributor, and the connector common to the numbering groups.

The accompanying drawing shows by way of example an automatic relay selector circuit of the two digit type adapted to serve 100 lines numbered from 01 to 00 but on which,

for greater simplicity, only five subscribers' lines are shown. For greater clearness this drawing shows only three trunk lines on the ten, a single conversation line (terminating each auxiliary line), a single marker group 70 instead of two, and finally a single connecting chain.

In this example we have designated by

I. Each subscriber's line,

II. The trunk lines,

III. A conversation circuit or line (that of auxiliary line II²) comprising among others a feed group,

IV. A marker group formed by two counting chains and preceded by the regulator or impulse distributor,

V. The connecting circuit or connecting group or connecting chain common to the counting groups.

On the diagram shown on the drawing, the calling lines are represented in heavy lines, the called lines are indicated by dotted lines and the lines of the local circuits are indicated by thin lines.

For the purpose of simplifying the description which follows, the device forming the subject of the present invention is described by the elements of which it is constituted and at the same time this operation will also be described.

When the telephonic combination (not illustrated in drawing) is unhooked the wires 1 and 2 are connected across the said combination. The relay A (relay of the calling line) which, for this reason, is connected to the -pole of the central battery by means of the wires 1, 2 and 3, comes into action and connects the wires 1 and 2 respectively, to the wires 4 and 5 and connects the -pole to the wires 6 and 115, that is to say to the winding of the relay D' (damping relay on the calling side). This comes into action and connects the wire 8 of each relay C¹ C² C³ etc. (selecting relays of the auxiliary lines) respectively to the wire 9 of the speaking line 100 corresponding with each of the relays under consideration.

At this moment two conditions arise:

All the auxiliary lines II may be unoccupied or some of these lines may be occupied.

Hereinafter it is assumed that the auxiliary lines II¹ and II³ are occupied and that the auxiliary line II² is free.

One end of the windings of all the relays C are branched by means of the wire 13 and the relays L (releasing relays) and K (guarding relays) of the corresponding speaking line, from the -pole of the central battery. In order that one of the relays C can come into action it is necessary, when unhooking the combination, to connect the +pole of the battery to the other end of the winding of the relay in question. This connection is effected by the speaking line of the auxiliary line II², that is to say by the following circuit: 115

—pole of the battery, contact of the rest relay L, wire 13, winding of relay C² of the subscriber's line No. 17 (which is assumed to be that of the calling subscriber), rest contact of the relay, wire 8, working contact of relay D¹, wire 9, rest contact of the relay K, wire 100 and +pole of the central battery (by means of the working contact of the relay K of the preceding speaking line which it has been assumed is engaged).

10 The connection with the +pole of the battery, which connection determines the bringing into action of the relay C cannot be effected except by means of one line at the time, whether the lines are free or engaged.

15 The relay D¹, when coming into action, closes all the circuits passing through its working contacts, a single one of the relays C is placed under tension, all the others being on a non-supplied circuit.

20 The relay C² comes into action, thus determining a series of operations which take place almost simultaneously and which are described separately hereinafter.

25 When the relay C² comes into action, the contact of its winding leaves the wire 8 so as to be connected to the wire 14 which causes the winding of the relay C² in question to be connected in series with one end of the winding of the relay B, (relay for cutting off the supply) the other end of the winding of relay B being permanently connected to the +pole of the battery.

30 The relay B when it comes into action, cuts off the supply of the subscriber's line, establishes the working circuit of the relay A by the connection of the wires 3 and 6, separating the +pole of the battery from the wire 83, causing the relay D' to return to rest and separating the wires 78 and 79 which serve to prepare the called side.

35 When the relay C² comes into action it connects the wires 4 and 5 respectively to the wires 11 and 12 which lead to the two poles of the central battery by means of the windings of the relay E (speaking relay on the called side).

40 This latter relay in turn comes into action and connects the +pole of the battery to the wires 15 and 16. As the wire 15 is connected to the winding of the relay K, this comes into action, cuts the circuit 9—100 and establishes the circuit 100—101 (which results in the occupation of the line of the auxiliary line II²); the relay K connects, on the other hand, the +pole of the central battery to the following line by means of the wire 100 passing from the preceding line and by means of the wire 104 in such a manner that the +pole of the battery can only be connected to one of the lines at a time.

45 The relay K also connects the +pole of the battery to the wire 17 which ensures general guarding during the whole duration of the conversation. The relay K also connects the

—pole of the battery to the wire 18. This same relay also connects the wires 21 (connected to different impulse distributors) respectively to the wires 102 and 103 which lead to the winding of the relays P and P¹ (connecting relays for the impulse distributors) by the rest contacts of the relay O (the function of which being to separate the lines of the impulse distributors) and by the wires 104 and 105.

50 If the first impulse distributor is disengaged the relay P is excited by the current passing through the following circuit:

—Pole of the central battery, winding of relay P, rest contact of this relay, wire 104, rest contact of relay O, wire 102, working contact of relay K, wire 21 of the first impulse distributor, rest contact of relay R (guarding relay for the impulse distributor) and +pole of the battery.

55 When the relay P comes into action the contact of this winding leaves the wire 104 and is again connected to the guard wire 23 which is connected to the +pole of the battery by means of the wire 17 and by means of the rest contact of the relay N (releasing relay for the impulse distributors).

60 On the other hand the relay P which is in action connects (by means of the wire 18, rest contact of relay N and wire 20) the —pole of the battery to the wire 22 connected to the winding of the relay R connected to the +pole of the battery; the relay R thus comes into action.

65 The other working contact of the relay P connects the —pole of the battery to the wire 106 which results in the excitation of the relay O which cuts the circuits 102—104 and 103—105.

70 Moreover the wire 16 being connected to the +pole of the battery by reason of the locking of the relay E, the relay S of the impulse distributor comes immediately into action (by reason of the closure of the circuit by means of the wire 28) and locks itself at the same time as the relay R.

75 The relay S in coming into action determines the coming into action of the relay T (dialing relay) by reason of the closing of the following circuit:

80 +Pole of the central battery, working relay R, wire 26, contact of the working relay S, wire 31, contact of rest relay U, wire 32, winding of the relay T, resistance r and —pole of battery.

85 On the other hand in coming into action the relay K has produced the excitation of the relay L (by means of the wire 17) and that of the relay M by means of the wire 17, rest contact of relay N', wire 34.

90 The relay M closes amongst others the contacts to which lead the wires 17 and 15 which results in holding the relay K in auto-excitation whilst the dialing impulses take place.

95 The operations above described take place

almost instantaneously by the simple unhooking of the combination at the calling station. The circuit is therefore ready to receive the impulses of the dialing dial with a view to selecting the called station.

If the first impulse distributor was engaged its wire 21 will have been separated from the + pole of the central battery by reason of the coming into action of the relay R; the + pole of the battery will have been connected to the wire 21 of the second distributor by means of the wire 27 and the rest contact of the relay R'. In this case the relay P' will have come into action and will have engaged the second distributor.

If all the impulse distributors are occupied the last of the relays connects the + pole of the central battery (wire 27) to the wire 33. If during occupation a combination is unhooked at another station the relay Q comes into action and connects (by means of the wire 23) the wire 29, to the + pole of the battery and excites the relay N which as herein-after described releases the engaged signal.

In the following example it is assumed, that the station No. 17 calls the station No. 90.

For this purpose the first subscriber inserts his first finger into the opening of the movable dialling disc opposite the Figure 9 and turns the disc in question. This movement of the dialling disc produces nine cutting operations of the line having for its object to interrupt nine times the excitation of the line relay E. This relay will connect and disconnect the + pole of the central battery nine times to and from wires 15 and 16. The relay S will occupy nine times the position of rest and nine times in succession the rest position and nine times in succession the operating position. At the first interruption the relay S returns to rest, cuts the circuit 26-31, and establishes the circuit 26-110, contact of working relay, wire 58, winding of relay U, resistance r and - pole of the battery.

Simultaneously the relay S connects the wire 26 (+ pole of the battery) to the winding of the relay V (intermittent guarding relay) by means of the wire 39. The relays U and V come into action.

In coming into action the relay U cuts the circuit 31-32 and establishes the circuit 31-59; on the other hand it closes the exciting circuit 37-58 cuts the circuit 40-61 and closes the circuit 40-41. The wire 26 (+ pole of the battery) is then connected to the first relay of the tens commutator by means of the following circuit.

+ Pole of the battery, contact of working relay R, wire 26, contact of working relay V, wire 40, contact of the working relay U, wire 41, contact of the rest relay W, (movable relay), wire 42, contact of the dialling rest relay j, wire 43, the rest contact of the dialling relay h, wire 44, the rest contact of the dialling relay f, wire 45, rest contact of

the dialling relay d, wire 46, rest contact of the dialling relay b, wire 47, winding of the dialling relay a.

The relay a comes into action and holds itself in excitation, being connected to the + pole of the battery by means on the one hand, of the wire 114, and on the other hand by the wires 48, 49, 50, 51, 52, 53, 54, 55, 56 and 57.

In coming into action the relay a connects, by means of its working contact, the wire 64 to the wire 65 and thus prepares the relay b for the second impulse.

After the first interruption the relay S again comes into operation and cuts the circuits 26-39 and 26-110 and closes the circuit 26-31. The new circuit formed is as follows:

Wire 26 (+ pole of the battery), working contact of relay S, wire 31, working contact of relay U, wire 59, common point of the winding of the relay T and the resistance r and the - pole of the battery. The relay T which has remained in auto-excitation by means of its working contact and the wires 26 and 32 returns to rest, the two ends of this winding being placed at the same potential.

By the second interruption determined by the dialling disc, the relay S again comes to rest, cuts the circuit 26-31 and closes the circuits 26-110 and 26-39. The relay T being kept at rest the wire 110 is connected to the wire 60 (common point of the winding of the relay U and of the resistance r^1) and it is the relay U which, this time, is short circuited as it is connected to the + pole of the battery, on the one hand, by the wires 37 and 58 and on the other hand by the wire 60.

The relay U comes to rest and connects the wire 40 (+ pole of the battery) to the wire 61, the rest contact of the relay T, the wire 63, the rest contact of the relay W, the wire 64, the working contact of the relay a, the wire 65 and the winding of the relay b.

The other end of this relay being branched to the - pole of the battery, the relay b comes into operation and holds itself in auto-excitation by means of the wire 55.

When coming into operation the relay b has broken the circuit 55-56; the relay a then again returns to rest.

The relay b has disengaged the wire 46 of the relay a and established the circuit 46-66 and has thus prepared the relay c for the third impulse and so on.

It may be mentioned that the odd impulses are transmitted along the wire 42 and are recorded by one of the relays a, c, e, g, i, whilst the even impulses are transmitted along the wire 64 and are recorded by one of the relays b, d, f, h, j. The same impulse cannot therefore be recorded by more than one relay, which renders incorrect dialling impossible.

It may be mentioned, on the other hand,

that the relays T and U occupy the working position for odd impulses, whilst they occupy the rest position for even impulses.

After the ninth interruption, determined by the dialling line, the relay *i* of the commutator for the tens becomes locked and as the figure 9 is the last of the series of the tens (as it is assumed that the called station is the station number 90) the relay *i* will be held in auto-excitation by means of its working contact and the wire 48.

In the working position the relay *i* also establishes connection between the wires 73 and 74. The relay *v* coming into action immediately the first impulse is transmitted by the dialling line remains excited by reason of its special characteristics during the whole duration of the same series of impulses.

When it is locked the relay V connects, amongst others, the + pole of the battery to the wire 37 which leads to the winding of the relay X (relay for preparing the mutations) which immediately comes into action and holds itself excited until the relay V, which controls it, is unlocked.

If the time which lapses between two series of impulses is relatively long with regard to two successive impulses, of the same series, the relay V has time to return to rest after the first series of impulses and connects the wire 26 of the battery to the circuit formed by the wire 67, the working contact of relay X (which is still in operation as it is sluggish), the wire 68, the rest contact of relay W, the wire 9, and the winding of the relay W which comes into action in order to cut out the circuits 41-42 and 63-64 and to establish the circuits 41-70 and 63-71 so that the second series of impulses is directed to a commutator for units which operates in a similar manner to that of the commutator for the tens.

Shortly after the relay X comes to rest.

At the end of the second series of impulses the relay *y* comes into operation and remains locked by means of its working contact and the wire 114 which is always connected to the + pole of the battery.

The relay *i* of the commutator for the tens and *y* for the commutator for the units are thus excited.

The numerical order of *i* being 9 in the commutator for the tens and that of *y* being 0 in the commutator for the units, there has been formed the number 90.

An instant after the end of the second series of impulses, the relay V comes to rest and connects the wire 26 (+pole of battery) to the wire 67, the contact of the relay X, returned in the working position (at the same time as the relay V) the wire 68, the contact of the working relay W, the wire 72, the contact of the working relay Y, (relay for placing the called lines under ten-

sion) which came into action at the same time as X and the wire 73.

The relay V also connects the + pole of the battery (by means of the working contact of relay *i*) to the wire 74 which leads to the winding of the relay Z⁹ (relay for the tens) representing the ninth tens. The same relay also connects the + pole of the battery to the wire 77 corresponding to 0 of the series of units.

The relay Z⁹ comes into action and connects by means of the wire 77, the wire 78, the rest contact of relay B of the called station, the wire 79 and the rest contact of relay D (relay for preparing the called side); + pole of the battery to the winding of the said relay D which comes into action and is held in excitation by being branched to the + pole of the battery by the rest relay B and the wire 88.

Shortly after the relay V has come to rest the relay X returns to rest, cuts the circuit 67-68 and establishes the circuit 67-113. By reason of this fact the + pole of the battery is connected to the winding of the relay N by means of the rest relay V, the rest contact of relay X, wire 113, working contact of relay Y, wire 30, contact of working relay P and wire 29.

The relay N comes into action; it releases on the one hand the impulse distributor which, from this moment becomes available for the establishment of a new communication; the relay N cuts, on the other hand, the circuits 17-34 and establishes the circuits 17-35 for connecting the wire 17, (+pole of the battery) to the relay C of the called subscriber, this connection being obtained by the closing of the following circuit.

+ Pole of the battery, contact of the working relay K, wire 17, contact of the working relay N, wire 35, working contact of the sluggish relay M, wire 87, rest contact and winding of relay J, wire 86, second working contact of relay M, wire 85, multiplied at all the relays D, wire 84, working contact of relay D corresponding to the called station, wire 8 and relay C² of the called station.

This relay of which one end of the winding is connected to the - pole of the battery comes into action, cuts its winding from the wire 8 and connects it with the wire 14; the relay B of the called subscriber comes into action and cuts on the one hand the guarding circuit of the relay D which returns to rest and on the other hand cuts off the supply to the line.

In coming into action the relay C² reconnects, on the one hand, the wires 4 and 5 to the wires 11 and 12, on the other hand, the wires 88 and 89 to the wires 90 and 91.

As the relay A remains at rest when the station is the called station the wires 4 and 5 are separated. The line of the called station is thus branched by means of the rest relay A, to the wires 88 and 89. When the relay C

is in operation the wires 88 and 89 are connected to the calling relay H. Shortly after the coming into action of the relays J and C², the sluggish relay M, from which the supply has been cut off by the relay N, returns to rest, cuts the circuit 35-87 and closes the circuit 35-36 for the purpose of reconnecting the + pole of the battery to the wire 96 which determines the bringing into operation of the calling apparatus.

The calling current supplied by the wire 98 passes through the line of the called station by reason of the formation of the following circuit:

Wire 98, rest contact of relay H, wire 90, contact of relay C² of the called subscriber, which is in operation, wire 88, contact of the rest relay A, wire 1, condenser and bell of the called subscriber, wire 2, second rest contact of relay A, wire 89, second contact of working relay C², wire 91, second contact of rest relay H (calling relay for the line), winding of relay H and - pole of the battery.

The relay H is not excited when its winding is traversed by alternating current but is excited when its winding is traversed by continuous current.

When the called subscriber has unhooked his combination and consequently disconnected his condenser from the line a continuous current passes through the line. The relay H comes into action and holds itself in auto-excitation by the wire 36.

The relay H thus interrupts the calling circuit and establishes the circuits 90-93 and 91-92.

The relay G (speaking relay on the called side) which constitutes the self supply of the called subscriber comes into action and definitely loops the speaking circuit by closing the circuits 93-95 and 92-94. From this moment conversation can take place.

For releasing the circuit at the end of the communication it is necessary for the two subscribers to suitably rehook their combinations.

In order to prevent a subscriber from forgetting to rehook his combination the first of the two subscribers who normally effects this operation determines the transmission, to his correspondent, of a conventional phonic signal "hang up". This signal which is received in the receiver of the station of which the combination has not yet been hooked up is continuous and sufficiently strong so as to enable it to be heard at some meters from the instrument.

If it is assumed that it is the called station where the combination is hung up first the wire 17 is connected to the wire 107 by the relay H which is in operation. In coming to rest the relay G connects, by its rest contact, the wire 17 (+ pole of the battery) to the wire 108 which leads to the winding of the relay SR.

This relay comes into action and determines by means of the wire 109 the transmission of the signal "hang up" over the calling line. If however it is the calling station where the combination has been hung up first the relay E effects a similar operation to that above described and the signal "hang up" is transmitted to the called station.

When the combinations have been hung up on both stations the relays E and G come to rest and cut the speaking line from the central battery. The relay K comes to rest immediately and the short interval of time which elapses between the unlocking of the relay K and the unlocking of the sluggish relay J (differentiation relay between the called, free or engaged line) enables the relays B and C of the called station and of the calling station to return to rest. When the relay L subsequently comes to rest it connects the - pole of the battery to the wire 18 for preparing the circuit for the establishment of a fresh communication.

If in the case under consideration the subscriber's station No. 90 had been engaged the relay J would not have been able to return to the locking position and the sluggish relay M, in coming to rest, would have connected the wires 17 (+ pole of the battery) to the winding of the relay F (engaged relay) by means of the wire 35, the rest contact of the relay M, the wire 36, the rest contact of the relay J and the wire 97.

The relay F thus excited closes the operating circuit (m-m) of the signalling device and connects the wire of the line 95 to the engaged circuit by means of the wire 38.

The conventional signal is thus noticed in the receiver of the calling subscriber who will thus hang up his combination so as to release the central members.

The improved automatic selecting circuit adapted for telephony or the transmission of signals to a distance and illustrated diagrammatically in one form of construction may be provided with any suitable number of subscribers' stations and the members illustrated in the drawing may be of a size, dimensions, proportions and constitution of any suitable nature without departing from the scope of the present invention which is characterized by the fact that in relation to automatic telephone systems proposed and carried out hitherto, the new device described above only requires with an equal number of subscribers very simple standardized members of reduced number whilst ensuring considerable security in the establishment of communications of which the secret is effectively guarded.

I claim:-

1. Automatic relay selector circuit for telephony, said circuit comprising in combination with a network of trunk lines (II), each terminating in a conversation line (III),

marker groups (IV) cooperating with a common connecting circuit (V) and individual equipments (I) for the subscribers' lines, the individual equipment of each subscriber's line including a line-reversing relay (A) with two pairs of contacts for connecting, when the subscriber's line (1, 2) is idle, with its incoming trunk (88, 89), and when operative, that is, only when the subscriber's station is the calling party, the said subscriber's line with the outgoing trunk (4, 5), the said two links (88, 89 and 4, 5) being individual to each equipment (I) of a subscriber's station.

15. 2. An automatic relay selector circuit for telephony as set forth in claim 1, in which the incoming and outgoing links (88, 89 and 4, 5) of each individual equipment (I) of the subscriber's station intersects a network of trunk lines (II), the number of which is only a fraction of the number of the subscribers' lines, said trunk lines each comprising, arranged in parallel, an incoming trunk (90, 91), an outgoing trunk (11, 12), a circuit (85) for controlling the incoming trunk, a circuit (9) for controlling the outgoing trunk and a locking circuit (13), means for causing each intersecting of the trunks of a subscriber's station with a trunk line, including a single selector relay (C¹, C², C³ . . .) effecting simultaneously, when it is operative, and by means of two pairs of contacts, on the one hand, the connection of the incoming link with the incoming trunk (90, 91) and, on the other hand, the connection of the outgoing link (4, 5) with the outgoing trunk (11, 12) one of the two links being automatically insulated from the corresponding subscriber's line (1, 2) by the reversing relay (A) from the said subscriber's line, selectively according to whether the said subscriber is the calling or the called party.

3. Automatic relay selector circuit for telephony as set forth in claim 1 each individual equipment (I) of the subscriber's line comprising two connecting relays (D, D¹), each having as many contacts as there are trunk lines (II), the movable contacts of these two relays being, on the one hand, connected in multiple between each other, and, on the other hand, connected respectively to the selector relays (C¹, C², C³ . . .) serving said individual equipment of the subscriber's line, the work contacts of one connecting relay (D¹) being connected respectively with the control circuit (9) of the outgoing trunk (11, 12) of the corresponding trunk lines and operating when the station is the calling party, while the work contacts of the other connecting relay (D) are connected respectively to the control circuit (85) of the incoming trunk (88, 89) of the same trunk lines and operate when this station is called, this latter relay comprising in addition a

prime circuit (78, 79) and a circuit (83) for sustaining its auto-excitation.

4. An automatic relay telephone selector circuit as set forth in claim 1, including condensers and a conversation line connecting together the outgoing trunk (11, 12) and the incoming trunk (90, 91) of the same trunk line (II), the several lines being mounted in cascade and each line comprising a feed group which is formed by two relays (E—G), feeding respectively the outgoing and the incoming trunks, the feed relays (E) of the outgoing trunk, by means of its work contacts, controlling a keeper (K), in its turn controlling a guard relay (L) for liberating the whole automatic selecting circuit, and, on the other hand, a reducer relay (M) to close the excitation circuit of the selector relay (C¹, C², C³ . . .) of the called subscriber, said selector relay being adapted to be put in series with a pilot relay (J) closing equally the circuit (96) of the call signal and the circuit (97) of the busy signal.

5. An automatic relay telephone selector circuit, said circuit comprising in combination with individual equipment (I) of the subscriber's lines and a network of trunk lines (II), a connecting circuit (V) common to a plurality of markers (IV), in their turn forming a circuit common to all the trunk lines (II), each of the counting groups (IV) comprising a plurality of counting chains, each formed of ten counting relays, the number of said chains corresponding to the number of digits forming the subscriber's number, each of the counting chains being actuated respectively according to the numbering of the units, the tens and so on, and the relays composing each chain serving respectively the decimal groups in connection with which the chain is actuated.

6. In an automatic relay telephone selector circuit, as set forth in claim 5, the counting chains, being similar to each other, whatever be the rank they occupy in the decimal order, said chains each including relays excited by means of two distinct circuits (42 to 47 and 48 to 57), one of which is traversed by the odd impulses of the current traversing the rest contact of each of the even relays, the other circuit being traversed by the even impulses shunted on each of the odd relays.

7. An automatic relay telephone selector circuit, as set forth in claim 5, including an impulse distributor relay preceding all the counting chains of the same marker group (IV) said relay subdividing the current impulses emitted by the counting dial of a subscriber's station into odd impulses which are directed on to the odd counting relays of a counting chain relay and into even impulses which are directed on to the even counting relays of said counting chain.

8. An automatic relay selector circuit comprising counting groups, the relay impulse

- distributor of each marker group (IV) being combined with a commutation device of the decimal order form, two control relays (V, X) and a reversing relay (W), the two control relays acting reciprocally so as to direct the current impulses emitted by the numbering or counting dial respectively on to the different counting chains, beginning with those corresponding to the highest rank in the decimal order.
9. An automatic relay telephone selector circuit comprising, in combination with individual equipments (I) of the subscriber's line and with a network of trunk lines (II), each terminated by a conversation line (III), of counting groups (IV), each preceded by an impulse regulator, said automatic circuit being characterized by the fact that all the counting groups are connected to a single connecting group chain circuit (V), formed by ten relays (Z), controlled individually by a work contact of each of the counting relays of the counting chains of the decimals (tens) of each counting group, each of said relays (Z) of the connecting circuit controlling in turn ten contacts, the fixed part of which ends at the control circuit (85) of a called subscriber's line, the movable part of each of said contacts terminating at the work contact of each of the counting relays of the counting chain of the units in each of the marker groups (IV).
